ELECTRICAL CONNECTOR

Cliff Baker, Los Angeles, Calif., assignor of one-half to Julius L. Mason, Encino, Calif.

Application January 18, 1943, Serial No. 472,653.

16 Claims. (Cl. 173—328)

1

This invention has to do generally with electrical connectors, and relates particularly to improvements in connectors of the type now commonly employed in airplane electrical circuits, though of course capable of other uses, comprising a body containing an insulation plug or core carrying one or more normally inaccessible terminals required to be exposed for soldering or other mode of attachment to cable conductors.

Among the most important features and characteristics to be desired in such connectors are facility and speed with which the core terminals can be made accessible for attachment to the conductors, and the connector then restored to normal condition. Essential also is the greatest possible precaution against parts of the connector becoming lost or disarranged so as to necessitate replacements or cause confusion and delay in making up the completed attachments with the conductors. The present invention has for its primary purpose the accomplishment of these objectives more completely and to a higher degree of perfection than have been obtainable by any other forms of electrical connectors of which I am aware.

Many of the conventional connectors have in common with the invention the general features of a body or shell containing the terminals which normally are completely received in the body and therefore require exposure for connection with the conductor wires. One common method of rendering the terminals accessible is to provide a sectional body, parts of which are removed to expose the terminals, and then reassembled after all connections are made. The use of such connectors, as well as others, consumes more time than is most desirable because of the required manipulations and the necessity for the worker's having to handle and reassemble separated parts.

In accordance with the invention I have provided a connector capable of utmost speed in manipulation, and having all the advantages resulting from the fact that its use involves no removal and replacement of parts. The present connector is primarily characterized in that the core assembly is releasably held in its normal or retracted position within the body, and its projected or terminal exposing position, between which positions the core is quickly movable axially within the body simply by the application of pressure against the exposed ends of the core. The core holding means has detent characteristics in that for all purposes of withstanding normal pressures exerted against it, the core remains positively held in either of its two posi-

2

tions, but is releasable from and engageable with the holding means by snap-type action upon the exertion of abnormal core shifting pressures. According to the preferred construction, the body or shell of the connector is made in sections constituting the detents for releasably holding the core as described. By yieldably resisting spreading or radial movement of the body sections, and providing them with internal detent shoulders, the body assembly is adapted in a simple and practical manner to serve the dual purposes of a housing for the core and a releasable core holding mechanism.

The above mentioned as well as additional features and objects of the invention will be more fully understood from the following detailed description of a typical connector construction embodying the invention. Reference is had throughout the description to the accompanying drawing, in which:

Fig. 1 is a view taken in the aspect of line 1—1 of Fig. 3 showing the connector in longitudinal section, the core assembly appearing in elevation and in advanced position;

Fig. 2 is a similar view showing the core in retracted position;

Fig. 3 is a cross-section on line 3—3 of Fig. 2; and

Fig. 4 is a cross-section on line 4—4 of Fig. 1. The connector assembly may be described generally as comprising a tubular body 10 having an insulation core or plug 11 normally contained within the body in the retracted position of Fig. 2, and movable axially within the body to and from the projected position of Fig. 1 by the application of end pressure against the core, all as will presently appear. The body has sectional characteristics giving it capacity for radial spreading, and preferably is split longitudinally to form equal sections 10a and 10b engaged along their overlapping edges as indicated at 12, see particularly Fig. 3. The overlap 12 may be terminated intermediate the ends of the body to provide shoulders 13 maintaining the body sections in exact longitudinal mating relationship. One end portion of the body is externally threaded at 14 for connection with a conduit coupling in the usual manner. The body also carries the tubular coupling nut 15 internally threaded at 16 and having an angular shoulder 17 engageable with the tapered surface 18 of the external body flange 19. The body sections normally are maintained in radial inter-engagement and yieldably held against spreading, by a split loop spring 20 seated within an annular groove 21 between the threads 14 and

the tapered shoulder 18. At this point it may be mentioned that spring 20 is snapped into the groove 21 after placement of nut 15 on the body, the spring thereafter serving to prevent removal of the nut from the body. End 10c of the body may contain suitable indicia, such as the polarizing groove 22 for orientation of the coupling in accordance with the positions of the terminal sockets.

The core 11 may be formed of any suitable electrical insulation, such as a phenolic condensation product, and is shown to include the conventional assembly of a main cylindrical section 23 having enlarged diameter end flange or head 24, and a back-up disc 25. The core assembly may contain any suitable number and arrangement of metallic electrical terminals or pins 26, two being shown as typical. These terminal pins may be of the usual form comprising an enlarged diameter socket portion 27 contained within a bore in the core section 23 and adapted to receive a conductor prong inserted through opening 28 into the socket 29. The opposite end of the pin extends through the back-up disc 24 and is formed with the usual soldering socket 30 for attachment to the conductor wire. The terminal pins are retained within the core assembly by engagement of the disc 24 with the end of the larger diameter socket portion 27 of the pin. The invention is independent of the particular type of terminal pin to be used, the illustrated form being conventional and therefore selected for purposes of description.

Normally the core assembly 11 is retained in what is referred to as the retracted position of Fig. 2, where the terminal ends are entirely contained within the body. Location of the core in this position is predetermined by engagement of the head 24 with the internal annular body shoulder 32. The core is releasably held against movement toward the projected position of Fig. 1, by engagement of the tapered face 33 of disc 25 with arcuate shoulders 34 of corresponding angularity formed on the inside of the body sections 10a and 10b. As best illustrated in Fig. 3, shoulders 34 disappear toward the mating edges of the body sections. As will appear, by virtue of the sectional characteristics of the body and the action of spring 20, shoulders 34 serve as detents releasably holding the core assembly in its retracted position.

The projected position of the core is predetermined by engagement of the angular disc face 33 with shoulders 35 formed inside the body sections at or near the end thereof. As shown in Fig. 2, shoulders 35 preferably are of arcuate extent, disappearing toward the mating edges of the body sections similar to the detent shoulders 34. It will be understood however, that if desired, shoulders 35 may be made continuously annular within the body and at no size diminution, should it be desired to prevent removal of the core assembly from the body other than by dismantling the sections. Formation of the shoulders 35 as illustrated has the advantage of permitting the core assembly to be thrust out of the end of the body without dismantling its sections. The core is releasably maintained in projected position and against pressure tending to move it into the body, by engagement of surface 36 on the head 24 with annular body section shoulders 37 similar to the arcuate shoulders 34.

Any suitable means may be provided to prevent rotation of the core assembly within the body,

while permitting its axial movement therein. As illustrative, the core may be maintained in predetermined orientation with the body by a key 38 extending between shoulders 32 and 35 and received within registering ways 39 in the core head and disc.

In considering the operation of the connector, assume the body to be assembled with the core in the retracted position of Fig. 2. Exertion of end pressure on the core at 40, by the finger or a tool, causes the body section to spread against the resistance of spring 20, permitting the core assembly to be thrust forward to the projected position of Fig. 1, openly exposing the terminal ends for soldering in the usual manner to conductor wires. The combined effects of such factors as the angularity of shoulders 37 and the tension of spring 20, may be adjusted to give the core adequate support against return movement during soldering operations, while avoiding the necessity for excessive pressure to return the core when soldering is completed. At this point it may be mentioned that should it be desired to remove the core completely from the body, as for replacement of core parts, continued end pressure on the core after reaching the position of Fig. 1, will cause the body sections to again spread and permit the core to be projected out of the body.

After the terminal connections are made, the core assembly may be returned to retracted position by exertion of pressure against the end at 41, causing the body to spread and shoulders 34 finally to close behind the core as it engages the stop shoulder 32. Again it may be observed that the combined effects of the spring tension and angularities of the core surface 33 and shoulders 34, may be adjusted to retain the core in position against the end thrust or polarizing pressure applied as the terminal sockets 27 are thrust against the conductor prongs.

From the foregoing it will be apparent that the core assembly is almost instantly movable between its retracted and projected positions, and that notwithstanding the speed and facility with which the connector may be so manipulated, the core is securely held in both positions against accidental displacement under all normal circumstances. Except for such purposes as removal of the core, the connector remains entirely self-contained and involves for its manipulation only the simple application of end pressure against the core in the manner described.

When finally joined to the companion prong assembly to be thrust into the pin sockets 27, the sleeve nut 15 is threaded on the usual threaded prong housing or shell, tightening the end of such housing or shell into engagement with shoulder 42. Thereafter the body sections 10a and 10b are maintained tightly engaged by the wedge action of surfaces 17 and 18 independently of the spring 20. Thus for assembly purposes the body is capable of spring-resisted spreading, but after final engagement with the prong assembly the body sections become rigidly held in engagement.

I claim:

1. An electrical connector comprising a tubular body, an insulation core within the body, a terminal element carried by the core, said core being movable axially within the body from a retracted position to an advanced position projecting said terminal out of the body, and releasable holding means engaging and maintaining the core against movement from said retracted position to said advanced position.

2. An electrical connector comprising a tubular body having open ends, an insulation core within the body, a terminal element carried by the core, said core being movable axially within the body from a retracted position to an advanced position projecting said terminal out of the body, and releasable holding means for maintaining the core against movement from one to the other of said positions, the core being releasable from and engageable with said holding means by manually exerting pressure axially and alternately against opposite exposed ends of the core.

3. An electrical connector comprising a body, an insulation core within the body and having accessible ends, a terminal element carried by the core, said core being movable axially within the body from a retracted position to an advanced position projecting said terminal out of the body while the core remains therein, and detent means associated with said body and releasably holding the core against movement from each to the other of said advanced and retracted positions, the core being releasable from and engageable with said detent means by exerting pressure axially and alternately against opposite ends of the core.

4. An electrical connector comprising a body, an insulation core within the body and having accessible ends, a soldering terminal element carried by the core, said core being movable axially within the body from a retracted position to an advanced position projecting said terminal out of the body while the core remains therein, and spring-pressed detent means associated with the body and releasably holding the core against movement from said advanced and retracted positions.

5. An electrical connector comprising a tubular body having a radially movable section, an insulation core within the body, an exposed terminal element carried by the core, said core being movable axially within the body from a retracted position to an advanced position projecting said terminal out of the body while the core remains therein, and means holding the core against axial movement from one of said positions and releasable by virtue of outward radial displacement of said body section.

6. An electrical connector comprising a tubular longitudinally split body having radially displaceable sections, an insulator core within the body, a terminal element carried by the core, said core being movable axially within the body from a retracted position to an advanced position projecting said terminal element out of the body, and spaced shoulders in said body sections engageable by the core and resisting its movement from each to the other of said positions, the core being movable from said positions by endwise pressure causing radial spreading of the body sections.

7. An electrical connector comprising a tubular longitudinally split body having radially displaceable sections, an insulator core within the body, a terminal element carried by the core, said core being movable axially within the body from a retracted position to an advanced position projecting said terminal element out of the body, spaced shoulders in said body sections engageable by the core and resisting its movement from each to the other of said positions, the core being movable from said positions by endwise pressure causing radial spreading of the body sections, and a spring about the outside of the body and resisting spreading of said sections.

8. An electrical connector comprising a tubular longitudinally split body having radially dis-

placeable sections, an insulator core within the body, a terminal element carried by the core, said core being movable axially within the body from a retracted position to an advanced position projecting said terminal element out of the body, spaced shoulders in said body sections engageable by the core and resisting its movement from each to the other of said positions, the core being movable from said positions by endwise pressure causing radial spreading of the body sections, a spring about the outside of the body and resisting spreading of said sections, and a coupling nut carried by the body and engageable with said sections to prevent their radial movement to positively lock said core against movement from said retracted position.

9. An electrical connector comprising a tubular body, an insulator core within the body, a terminal element carried by the core, said core being movable axially within the body from a retracted position to an advanced position projecting said terminal element out of the body, spaced stop shoulders limiting movements of the core to said positions, and means engaging and releasably holding the core against axial movements from each to the other of said positions.

10. An electrical connector comprising a tubular body, an insulation core within the body, a terminal conductor carried by and projecting beyond one end of the core, said core being movable axially and reciprocally within the body between a retracted position in which said element is contained within the body and an advanced position in which said element is projected out of an end of the body with the core remaining therein, and means holding the core in said advanced position against movement out of said end of the body, said holding means being releasable to permit removal of the core from the body through said end thereof.

11. An electrical connector comprising a tubular body, an insulation core within the body, a terminal conductor carried by and projecting beyond one end of the core, said core being movable axially and reciprocally within the body between a retracted position in which said element is contained within the body and an advanced position in which said element is projected out of an end of the body with the core remaining therein, releasable holding means for resisting movement of the core from one to the other of said positions, and means for locking said holding means to positively prevent the last mentioned movement of the core.

12. An electrical connector comprising a tubular body, an insulation core within the body, a terminal conductor element carried by the core, said core being movable axially and reciprocally within the body between a retracted position in which said element is contained within the body and an advanced position in which said element is projected out of the body, and means for positively locking said core against movement from said retracted position to said advanced position.

13. In a connector, the combination of a cylindrical housing having housed therein a connecting plug, a contact element carried by the plug, the housing being formed of more than one section, means for yieldably holding the sections together, and means formed on the inner surface of the housing adapted to cooperate with the plug for expanding the sections of the housing on axial movement of the plug, the axial movement of the plug within the housing acting to project the terminal element from the housing in one position

on movement thereof and to hold the contact element housed within the housing upon another position of movement thereof.

14. In a connector, the combination of a housing and a plug positioned within the housing, a contact element carried by the plug, the housing being formed of half sections and means for yieldably holding the half sections together, the plug being axially movable within the housing to advanced and retracted positions therein, an expansion cam ridge formed on the inner surface of the housing adapted to cooperate with the plug for expansion of the half sections of the housing on endwise motion of the plug within the housing, shoulder means formed within the housing for cooperation with the plug for holding the plug in advanced and retracted positions of axial movement within the housing, a collar means surrounding the housing, and cooperating means formed between the collar and the housing for holding the half sections from expansion, whereby the plug is locked in its position within the housing.

15. An electrical connector comprising a body, a core within the body, a terminal element carried by the core, said core being movable axially within the body from a retracted position to an advanced position projecting said terminal out of the body, cooperating means formed within the body and upon the core for releasably holding and maintaining the core against movement within the body from said retracted position to said advanced position.

16. An electrical connector comprising a body,

a core within the body, a terminal element carried by the core, said core being movable axially within the body from a retracted position to an advanced position projecting said terminal out of the body, cooperating means formed within the body and upon the core for releasably holding and maintaining the core against movement within the body from said retracted position to said advanced position, the said body being formed of plural sections, means for releasably holding the body sections together, and the cooperating means formed between the body and the core acting upon endwise movement of the core within the body to expand the body sections against the pressure of the said yieldable body means acting to hold the body together.
